UNITED STATES PATENT OFFICE.

JOHN H. FLOWERS, OF ENTERPRISE, OREGON, ASSIGNOR OF ONE-HALF TO JOHN O. RUTTER,
OF ENTERPRISE, OREGON.

MECHANICAL MOVEMENT.

No. 905,683.

Specification of Letters Patent.

Patented Dec. 1, 1908.

Application filed September 4, 1906. Serial No. 533,084.

To all whom it may concern:

Be it known that I, JOHN H. FLOWERS, a citizen of the United States, and a resident of Enterprise, in the county of Wallowa and 5 State of Oregon, have invented a new and Improved Mechanical Movement, of which the following is a full, clear, and exact description.

This invention relates to mechanical movements, and is particularly useful in connection with washing machines, churning, and devices of similar character in which an alternating rotary movement of certain parts is desired, or in which certain parts are to be 15 reciprocally rotated in one direction and then another.

The object of the invention is to provide a simple and efficient mechanical movement for driving washing machines, churning or devices of similar character from a continuous uninterrupted rotary motion, and giving the certain parts an alternating rotary movement.

The invention consists in the construction 25 and combination of parts, to be more fully described hereinafter and directly set forth in the claims.

Reference is to be had to the accompanying drawings forming a part of this specification, in which similar characters of reference indicate corresponding parts in all the figures.

Figure 1 is a side elevation of my device, showing parts of the same in one position; 35 Fig. 2 is a similar view, showing a part of the casing broken away and the container in a different position; Fig. 3 is an end elevation of my invention; Fig. 4 is a top plan view, and Fig. 5 is a cross section of the container.

Referring more particularly to the parts, 1 represents supports or standards of the usual construction, having their bases 2 adapted to be securely attached to a floor, 45 and having bearings 3 at their upper ends. A shaft 4 is rotatably mounted in the bearings 3 and extends laterally beyond one of the supports 1. A cylindrical casing 5 is mounted between the supports 1, the shaft 4 passes therethrough and is adapted to rotate 50 within suitable openings provided for the purpose in the sides 6. The casing is held rigid to prevent its rotation with the shaft 4 by means of transverse bolt bars 7 extending 55 between the supports 1 and abutting against

the lower portion of the casing. The under side of the casing is provided with a steam inlet 8 and a steam outlet 9, to permit steam to enter the same and escape therefrom for the purpose of heating the device interiorly. 60 A door or lid 10 is provided in the side of the casing and is secured in place by means of hinges 11 and a latch 12 of the usual construction.

A container 13 is rigidly secured upon the shaft 4 within the casing 5, and is adapted to rotate with the shaft 4. The container is semi-cylindrical; has end walls 20 and a flat side 14 provided interiorly with transverse cleats 15, for a purpose to appear hereinafter. The sides of the container are pierced by holes 16 to permit the entrance within the container of the water and soap-suds with which the casing is partially filled when the device is in operation, as well as more thoroughly to permit the steam to heat the same. The container has a lid or door 17 secured to it by means of hinges 18, and a latch 19 of the usual construction. The arrangement is such that in a certain position of the container the door therein and the door of the casing register, to permit the placing in or taking out of the clothes or other objects to be washed. The shaft 4 passes through the container as well as the casing.

Rigidly mounted upon the end of the shaft 4, which projects laterally beyond the support 1, is a flat member 21. Mounted upon the outer face of the member and projecting perpendicularly therefrom is a series 90 of pins 22 arranged successively in the arc of a circle having its center at the center of the shaft 4. A similarly curved plate or bar 23 having a plurality of perforations adapted to fit upon the ends of the pins 22 rigidly connects these ends of the pins, which constitute a double-faced rack adapted to be engaged on either face by a pinion. The member 21 has a projection 24 near its upper portion, and a projection 25 at the opposite 95 end of the member. An arm 26 extends from the support adjacent to the member 21 carrying at its free end a pin 27, against which the projection 24 is adapted to abut, limiting the rotation of the shaft 4. The 100 arm 26 has lateral projections 29. The projections 29 are provided with openings within which is a rod 30 having at its end a stop 31. A helical spring 32 surrounds the rod 30 between the projections 29. The 110

arrangement is such that the projection 25 or the member 21 abuts against the stop 30 when the member is rotated to a certain position, and by this means the rotation is limited. A collar 33 rigidly mounted on the rod 30 between the projections 29 compresses the spring when the member 21 strikes the stop 31, whereby the rotation is stopped with little or no jar, the spring providing a cushioning effect.

A support 34 adapted to be secured to a floor and having upwardly extending arms 35 provided at their upper ends with bearings 36 is located near the member 21. A shaft 37 is rotatably mounted within the bearings 36 and has an end projecting laterally beyond the bearings remote from the member 21, and upon this projecting end is mounted a pulley 38, to which power may be applied in the usual manner by means of a belt. A bracket 39, having its sides 40 joined by end plates 41 which are bolted in place, is pivotally mounted upon the shaft 37. Upon the sides of the bracket are bolted edge plates 42, between which and the sides 40 are formed bearings 43, 44 and 45. By means of the bearings 43 the bracket is pivotally mounted upon the shaft 37, upon which is also rigidly secured a pinion 46. The pinion 46 meshes with a second pinion 47 mounted in the bearings 44, which in turn meshes with a pinion 48 in the bearings 45. The shaft 49 of the pinion 48 extends toward the member 21 and has mounted thereon a pinion 50, the teeth of which are adapted to engage with the pins constituting the rack upon the member 21. It will be understood that the bracket 39 can be pivoted about the shaft 37, and when the pinion 50 engages the under face of the rack, the end of the bracket will be slightly depressed, while if the pinion 50 engages with the opposite side of the rack the end of the bracket will correspondingly be raised.

An upright 51 is secured to the floor near the end of the bracket 39, and has a plate 52 with laterally disposed ends 53, through which passes in suitable openings a rod 54 having an end adapted to abut against the under side of the bracket. A helical spring 55 surrounds the rod between the ends 53, and abuts against a rigid collar 56 upon the rod. The tension of the spring forces the rod upwardly against the underside of the bracket, thus pressing the gear wheel 50 upwardly against the under side of the rack when the engagement of the pinion is with that face of the rack. The rotation of the pulley 47 is transmitted through the intervening pinions to the pinion 50. As this rotates it rotates the member 21 through the rack, the latter moving with the rotation of the pinion 50. When the last pin of the rack 65 reaches the pinion, the same pivots about that

last pin, and as the bracket is forced upward the pinion simply turns about the last pin onto the upper side of the rack with which it meshes, thereby rotating the member 21 in an opposite direction. When the pin at the other end of the rack reaches the pinion the same operation is gone through in a reverse direction, the pinion merely pivoting about the last pin of the rack, to mesh therewith, and again reverses the direction of rotation of the member 21 and the shaft 4, to which the latter is secured. At the upper end of the upright 51 is a toe 57 adapted to engage with a projection 58 upon the bracket 39, to limit the upward movement of the latter, thereby insuring that the pinion 50 will not be thrown out of mesh with the upper face of the rack by the upward pressure of the spring 55. The arrangement is such that as one end of the rack reaches the pinion 50 the projection 24 strikes against the pin 27, thereby stopping the rotation of the member 21, while the pinion 50 pivots about the end pin onto the other face of the rack. Similarly, when the opposite end of the rack reaches the pinion 50 the projection 25 strikes the stop 31, to stop the rotation of the member 21.

The construction and arrangement of the details of the washing machine are such that when the pinion 50 meshes with the rack near the middle point of the latter, the flat side 14 of the container is substantially horizontal, and when the pinion is at the end of the rack, the inclination of the flat side 14 with the horizontal is a maximum; thus the clothes or other objects within the container are not rolled about, but are allowed to drop from one side to the other of the container, thereby thoroughly coming in contact with the water and soap-suds, which are agitated within the same and through the openings in its sides. The cleats 15 upon the side 14 are for the purpose of holding the objects within the container near one end thereof, while the flat side is approaching its maximum inclination, thereby permitting the objects to drop from one side to the other. The casing 5 is provided with a drain faucet 59 on its under side, by means of which the casing may be emptied of the water there within when the device is in use.

Having thus described my invention, I claim as new and desire to secure by Letters Patent:

1. A device of the class described, comprising a driven shaft, a member rigid with said shaft and having pins projecting laterally therefrom constituting a double-faced rack, a pivoted bracket having a pinion adapted to engage with each face of said rack, means for rotating said pinion, means for limiting the rotation of said shaft, and means for normally forcing said bracket toward said member.

2. A device of the class described, comprising a frame having stops, a driven shaft, a member rigid with said shaft and having projections, said member further having a 5 double-faced rack, a pivoted bracket having a pinion adapted to engage with each face of said rack, said projections being adapted to engage said stops to limit the rotation of said member, means for rotating said pinion, 10 and resilient means for forcing said bracket toward said member.

3. A device of the class described, comprising a driven shaft, a member rigid with said shaft and having a double-faced rack, 15 a bracket pivoted near one end, a pinion mounted in said bracket and adapted to engage with each face of said rack, means for forcing said bracket towards said rack, and means for rotating said pinion.

20 4. A device of the class described, comprising a frame having stops, a driven shaft, a member rigid with said shaft and having a double-faced rack, said member having projections adapted to engage said stops to limit the rotation of said member, a bracket 25 pivoted near said member and a pinion thereon adapted to engage with each face of said rack, means for rotating said pinion, means for forcing said bracket towards 30 said rack, and a stop for limiting the upward movement of said bracket.

5. A device of the class described, comprising a frame, a driven shaft, a member rigid with said shaft, said member having 35 a double-faced rack and projections, stops on said frame adapted to engage with said projections to limit the rotation of said member, a pinion movable in a substantially vertical direction and adapted to engage 40 with each face of said rack, and means for rotating said pinion.

6. A device of the class described, comprising a driven shaft, a member rigid with said shaft, said member having projections 45 and a double-faced rack, an arm having a pin adapted to engage with one of said projections, and a rod adapted to engage with another of said projections, a spring adapted to resist the movement of said rod, a pinion 50 adapted to engage each face of said rack, and means for rotating said pinion.

7. A device of the class described, comprising a driven shaft, a member rigid with said shaft and having a double-faced rack, 55 a support, a driving shaft carried by said

support, a bracket mounted upon said driving shaft, a pinion mounted upon said driving shaft, a second pinion carried by said bracket and adapted to engage with each face of said rack, means for transmitting 60 the rotation of said first pinion to said second pinion, and means for operating said driving shaft.

8. A device of the class described, comprising a driven shaft, a member rigid with 65 said shaft, a double-faced rack formed in the arc of a circle and mounted on said member, a support, a bracket pivotally mounted upon said support, a pinion carried by said bracket and adapted to engage with each face of 70 said rack, means for rotating said pinion, a spring adapted to force said bracket upwardly, and a stop adapted to limit the upward movement of said bracket.

9. A device of the class described, comprising a driven shaft, a member rigid with said shaft, said member having laterally projecting pins constituting a double-faced rack formed in the arc of a circle, a pinion movable in a substantially vertical direction and adapted to engage with each face of said rack, said pinion being adapted to pivot about an end pin of said rack to travel from one face to the other face thereof, means for forcing said pinion upwardly, means for 85 limiting the upward movement of said pinion, and means for rotating said pinion.

10. A device of the class described, comprising a frame, a driven shaft rotatably mounted upon said frame, a member rigid 90 with said shaft, a double-faced rack on said member, a support, a pivot shaft carried by said support, a bracket pivotally mounted upon said pivot shaft, a pinion carried by said bracket and adapted to engage with 95 each face of said rack, a second pinion upon said pivot shaft, means for transmitting the rotation of said second pinion to said first pinion, means for limiting the rotation of said member, a spring forcing said bracket 100 upwardly, a stop limiting the upward movement of said bracket, and means for rotating said second pinion.

In testimony whereof I have signed my name to this specification in the presence of 105 two subscribing witnesses.
